UNITED STATES PATENT OFFICE.

HARRIS RAYMOND TILL, OF CHICAGO, ILLINOIS, ASSIGNOR TO WESTERN ELECTRIC COMPANY, INCORPORATED, OF NEW YORK, N. Y., A CORPORATION OF NEW YORK.

VULCANIZING APPARATUS.

Application filed May 8, 1923. Serial No. 637,446.

This invention relates to vulcanizing apparatus and more particularly to apparatus of this nature in which an article is rotated during its vulcanization.

5 In the case of strand material especially in the form of a core sheathing, which is wound on a reel in a plurality of superposed layers, it is desirable that the supporting reel be rotated during the vulcanization 10 period to prevent the decentralization of the core within, or other deleterious deformation of the plastic sheathing which otherwise might be introduced by the pressure of the sheathed core in the various layers. 15 Since, in the manufacture of insulated electrical conductors in this manner, it is desirable to make the sheathed cores in as long continuous lengths as may be practicable, a reel completely filled and ready 20 for vulcanization is of considerable weight and requires a substantial support, as well as an appreciable amount of power for handling it during its transportation into and out of the vulcanizing apparatus, as 25 well as for rotating it therein during vulcanization.

It is an object of this invention to improve the apparatus for handling a carrier for vulcanizable material during the movements thereof incident to the vulcanization 30 of the material.

Another object is to rotate a reel within a nonrotatable vulcanizing oven by means located outside of the oven.

35 A further object is to move a carrier into and out of an oven on a carriage which also serves to support and permit the rotation of the carrier.

A still further object is to terminate 40 motive means, mounted upon the exterior of a vulcanizing oven door, in means responsive to the opening and closing of the door for engaging and disengaging, and thereby controlling the rotation of a reel containing 45 vulcanizing material within the oven.

In order to attain these objects there is provided in one embodiment of the invention, a carriage or truck having a plurality of wheels for engaging a track or way, each 50 end of the carriage being provided with suitable rollers, preferably grooved, upon which the peripheral flanges of the reel heads are placed. The track or way which may extend from the point at which the 55 reel is filled into the vulcanizing oven is

provided with a portion which may be removed when the carriage is within the oven to permit the closure of the oven door. A motor, preferably of the electrical type, is mounted upon the exterior of the door and is suitably connected through gearing, or otherwise, to a centrally located shaft extending through the door and terminating in a spider with a plurality of projections for engaging a corresponding number of 60 openings in the reel head nearer the door, for rotating the reel on the carriage rolls.

These and other objects not specifically mentioned will be clearly apparent from the following description and the accompanying drawings illustrating one embodiment of the invention:

Fig. 1 of the drawings is a perspective view of a reel of vulcanizable material in strand form mounted upon a carriage, ready 75 for insertion into an oven, a part of which is broken away, and also showing the means for rotating the reel upon the carriage, and

Fig. 2 is a sectional view, some parts being shown in elevation, of the vulcanizing 80 oven with the loaded reel in position for vulcanization.

As shown in the drawings in which like numerals designate similar parts throughout the various views, a cylindrical oven 10 having one closed end is mounted upon a base 11 located in a recessed portion of a floor. The other end of the oven is provided with a hinged door designated generally by the numeral 12. A pair of rails 13 are supported upon suitable brackets 14 mounted upon the interior of the oven and cooperate with removable rails 15 and floor rails 16 to provide a continuous track or way. This track or way may extend over the floor 95 to the point at which the reel is loaded. A carriage provided with a plurality of wheels 18 rotatably mounted upon end members 21 is adapted to be propelled along the track into or out of the oven. A plurality of rollers 20, preferably grooved, also mounted upon the end members 21 provide means for rotatably supporting flanged heads 23 of a reel 39.

Extending through the door 12 and supported by a suitable bearing and bushing member 25 is a shaft 26 upon the interior end of which is mounted a spider 27 having two projecting ends 28 for engaging two of a plurality of openings 29 in the head 23 105 110

- of the reel 39. Suitably supported by a bracket 30 mounted on the exterior surface of the door is an arrangement for rotating the shaft 26. This arrangement may take 5 any desired form such as shown, in which a motor operates through a gear reduction device to drive a gear wheel mounted on the external end of the shaft 26. Suitable means (not shown) is provided for fastening the 10 door when it is closed to make the joint between the end of the oven wall and the door sufficiently tight to prevent the escape of the heating medium from the oven during the vulcanizing process. Near the closed 15 end of the oven a conduit 35 is introduced into the oven and may be associated with a source of steam or other suitable heating medium.
- In the operation of the apparatus the reel 20 39 filled with vulcanizable material in strand form, such as a sheathed core, is placed upon the carriage with the peripheral flanges of the heads 23 resting in the grooved rollers 20. The loaded carriage is 25 then propelled along the floor rails 16, the removable rails 15, and the rails 13 into the oven 10. The rails 15 are then removed and the door 12 is closed. It may be necessary in some instances either to rotate the reel 30 39 slightly upon the rollers 20 or to rotate the shaft 26 so that the ends 28 will easily register with some of the openings 29 in the adjacent head 23. A valve (not shown) associated with the conduit 35 is then opened 35 allowing steam or other suitable heating medium to flow into the interior of the oven. The motor is then operated to slowly rotate the reel 39 upon the rollers 20 by means of the shaft 26 and the ends 28 of the spider 40 27 in engagement with openings 29 in the head 23 of the reel 39. When the material on the reel has been heated for a sufficient length of time, the valve controlling the supply of steam is closed and after the expiration 45 of the predetermined cooling period the motor is stopped. The door 12 is then opened, the removable rails 15 are replaced and the carriage containing the reel 50 of vulcanized material is removed from the oven over the track or way.

What is claimed is:

1. In a vulcanizing apparatus, a vulcanizing oven, a door therefor, a carrier containing vulcanizable material, friction reducing means engaging the periphery thereof for supporting the carrier within the oven, and means operating through an opening in the door for rotating the carrier on the friction reducing means.
2. In a vulcanizing apparatus, a vulcanizing oven, a door therefor, a way extending into the oven, a reel containing vulcanizable material, perforated heads for the reel, a carriage traversing the way, rollers thereon for supporting the heads, a rotatable shaft 65 extending through and supported by the door, a terminal therefor adapted to engage a perforation of a reel head when the door is closed, and motive means for the shaft mounted upon the exterior of the door to 70 rotate the reel upon the carriage.

3. In a vulcanizing apparatus, a vulcanizing oven, a door therefor, a reel containing vulcanizable material, a plurality of heads for the reel, one of said heads having an 75 opening therein, a support within the oven, a plurality of rollers thereon for engaging the peripheral edges of the heads and thereby support the reel, a driving member mounted on the door and adapted to engage 80 the opening in the head of the reel when the door is closed, and means for driving the member for rotating the heads upon the rollers.

4. In a vulcanizing apparatus, a vulcanizing oven, a reel for containing vulcanizable material in strand form, heads for the reel having circumferential peripheral portions, a support within said oven, a plurality of rollers therein for supporting the heads of 90 the reel, a shaft extending into the oven while the door is in closed position, a spider carried thereby and having a plurality of projections engaging a like number of a greater number of openings in one of the 95 heads for rotating the heads upon the rollers, and means mounted on the exterior of the door for rotating the shaft.

5. In a vulcanizing apparatus, a vulcanizing oven, a door therefor, a reel containing 100 vulcanizable material, a head therefor having a plurality of apertures, reel driving means mounted on the door comprising a driving shaft extending into the oven, a laterally extending member secured to said 105 shaft, and an element integral with said member cooperating with the apertures in a head of said reel for forming a driving connection therefor.

6. In a vulcanizing apparatus, a vulcanizing oven, a door therefor, a reel containing vulcanizable material and having a head provided with a plurality of groups of diametrically opposite apertures, a driving member designed to engage oppositely disposed apertures in said reel head, reel driving means secured to the door and having a shaft extending therethrough, and a member secured to the shaft and provided with means for engaging oppositely disposed 115 apertures in the reel head to rotate the reel.

In witness whereof, I hereunto subscribe my name this 28th day of April, A. D., 1923.

HARRIS RAYMOND TILL.
